UNITED STATES PATENT OFFICE

137,442

DESIGN FOR A HIGH CHAIR TRAY

Peter J. Nordby, Marietta, Ohio, assignor to Marietta Chair Company, Marietta, Ohio, a corporation of Ohio

Application September 20, 1943, Serial No. 111,165

Term of patent 3½ years

To all whom it may concern:

Be it known that I, Peter J. Nordby, a citizen of the United States, residing at Marietta, in the county of Washington and State of Ohio, have invented a new, original, and ornamental Design for a High Chair Tray, of which the following is a specification, reference being had to the accompanying drawings, forming part thereof.

Fig. 1 is a bottom perspective view of the high chair tray, showing my new design;

Fig. 2 is a bottom plan view;
Fig. 3 is a front elevational view;
Fig. 4 is a side elevational view; and
Fig. 5 is a view in perspective on an enlarged scale of the article as viewed from the top.

I claim:

The ornamental design for a high chair tray as shown.

PETER J. NORDBY.
